CLAIM

The ornamental design for a motorcycle gas tank, as shown and described.

DESCRIPTION

FIG. 1 a front left perspective view of a motorcycle gas tank incorporating a design according to the invention.

FIG. 2 a right rear perspective view of the motorcycle gas tank of FIG. 1.

FIG. 3 a top view of the motorcycle gas tank of FIG. 1.

FIG. 4 a bottom view of the motorcycle gas tank of FIG. 1.

FIG. 5 a front view of the motorcycle gas tank of FIG. 1.

FIG. 6 a rear view of the motorcycle gas tank of FIG. 1.

FIG. 7 is a right side view of the motorcycle gas tank of FIG. 1; and,

FIG. 8 a left side view of the motorcycle tank of FIG. 1.

The broken lines in FIGS. 1-8 are shown for illustrative purposes only, and form no part of the claimed design.

The broken lines which define the boundaries of the claimed design form no part thereof.
